PERPETUAL CALENDAR

Jonas Kaufman, Hutchinson County, S. Dak.

Application September 27, 1944, Serial No. 555,928

6 Claims. (Cl. 40—107)

This invention relates to a perpetual calendar, and is a continuation in part of my application Serial No. 520,854, filed February 3, 1944, for a patent on the same invention.

This invention can be used as a part of a desk set, as well as a wall calendar, and can be used as a permanent fixture in the front part of an automobile or truck, or may be placed upon the instrument board of an airplane or ship.

It requires setting but once a month and can be reset in a few seconds of time in such a manner that it currently shows consecutively each and every day of whatever month it may be set for. All the date-carrying parts of the calendar are resettable and hence do not have to be renewed.

It is an object of the invention to provide an improved means for adjusting the date indicating numerals occurring near month ends in such a manner that the correct week-day indication for such dates will be afforded by the calendar.

Speaking more specifically it is an object of the invention to provide a simplified gear operable means for adjusting in the correct manner date indicating numerals occurring near the ends of the months.

Other objects, advantages and features of invention will hereinafter appear.

Referring to the accompanying drawing, which illustrates what is at present deemed to be a preferred embodiment of the invention,

Fig. 1 is a front view of the calendar showing it somewhat in perspective adjusted for correct date indication for a month containing thirty-one days.

Fig. 2 is also taken somewhat in perspective, the calendar being viewed from the rear.

Fig. 3 is a horizontal section looking up from the line 3—3 of Fig. 2.

Fig. 4 is a horizontal section looking down from line 4—4 of Fig. 2.

Fig. 5 is a front face view of a shiftable plate having upon it the month-indicating numerals except those above 28.

Fig. 6 is a developed face view of the smaller of the rotatable auxiliary date-indicating blocks.

Fig. 7 is a developed face view of the larger date-indicating block.

Referring in detail to the drawing, the elongated, rectangular cover plate 9 as viewed in Fig. 1 has each of its end portions bent backwardly at a right angle thus providing it with the end flanges 10 and 11, said flanges being sufficiently wide to afford, in combination with the lower edge of the body portion of the plate of which

they form a part, a stable means for supporting the cover plate in an upstanding position upon a suitable horizontal surface. These flanges are suitably apertured to provide bearings for a rotatable screw rod 12 and for a non-threaded, preferably square rod 13, said rods being parallel, the rod 13 being spaced vertically below the rod 12.

Outside of the flange 11 the rods 12 and 13 are respectively provided with operating knobs 14 and 15 and outside of the flange 10 conventional keepers 16 are used to prevent the withdrawal of the rods.

The cover plate 9 has through it a large rectangular window or sight opening 17 above which are the week-day indicating letters 18 and through which are displayed date indicating numerals inscribed upon a shiftable rectangular date plate 19. This date plate is somewhat narrower and considerably shorter than the cover plate 9, but is similarly shaped, having backwardly directed end flanges 20 and 21. Said date plate has apertures 22 and 23 through which the rod 12 passes and is supported by said rod with its lower edge above the lower edge of the cover plate 9 so as to clear a table or other horizontal support upon which the device may be placed.

It will be seen that the shiftable date plate 19 has inscribed upon it a table of month day indicating numerals arranged in vertical columns and horizontal rows, the numbers of each column consecutively increased by seven when read downwardly, and the numbers of each horizontal row being progressively one higher as read from left to right.

Screw threads may be formed upon the rod 12 in any suitable manner. As shown in the drawing said rod is formed of two wire strands twisted upon each other in a uniform manner to function as screw threads, either of the apertures 22 and 23 or both closely conforming to the contour of the rod so that when it is rotated it will cause a shifting movement of the date plate 19 longitudinally of the cover plate.

The structural details of the number plate 19 are best shown in Fig. 5, from which view it will be seen that five rows of date indicating numerals are provided upon said plate, the second, third and fourth rows being partly duplicative of each other, according to well-known practice in perpetual calendar construction, the table of numerals thus provided beginning with "1" and ending with "28" so that by shiftably adjusting the date plate 19 in relation to the week day designations 18 February week days may be indicated for any

year in which February does not have more than twenty-eight days.

Describing next the means for indicating the week days upon which days of the month above "28" fall, a rectangular sight opening 25 is provided through the date plate 19 at about the midlength of said plate at the right hand end of the fourth row of numerals which row ends with "28." The length of this sight opening extends across three columns of numerals and its width is somewhat greater than the vertical dimension of the size of date-indicating numerals shown.

Also, through the lower left hand corner portion of the date plate 19 is another sight opening 26. This opening is of the same width as the opening 25, but its length is only about two-thirds that of the latter opening, that is to say, sufficient to disclose numerals of a size to occupy two instead of three of the columns of date-indicating numerals.

Two rotatably adjustable number blocks 25a and 26a are provided to display certain month end numerals through the aforesaid sight openings 25 and 26 respectively. The block 25a has through it a square, centrally located longitudinal passage through which the already mentioned rod 13 extends, the block being held upon the rod in the position shown to rotate therewith. The block is preferably loose upon the rod in regard to longitudinal movement, but when the parts are assembled the block is kept from longitudinal movement by a pair of flanges 27 formed by outbending portions of the metal cut out from the plate 19 in making the opening 25, said flanges having apertures sufficiently large to receive rotatably the rod 13.

The block 26a is secured to a stub shaft 28, one end portion of said shaft having a bearing in the lower part of the end flange 29 of the plate 19 and the opposite end portion of this shaft having its bearing in a flange 29 formed by outbending a part of the material cut out to form opening 26. That end portion of the stub shaft which has its bearing in flange 29 has secured to it a driven gear 31 which meshes with a driving gear 32 fixed to the adjacent part of the shaft 13.

Flange 29 is provided with downwardly directed lip 29a which loosely overlies the upper part of the outer face of gear 32 to keep said gear in mesh with gear 31 as said gear 32 slides along the square rod 13 during the shifting movement of the date plate 19.

The rotatable blocks 25a and 26a are both square as viewed in cross section so that the date-indicating numerals may be conveniently placed upon them. The faces of these blocks are shown in a developed fashion in Figs. 6 and 7.

The gears, shafts and blocks which have been mentioned are assembled in such a relation to each other that they cooperate properly, in conjunction with the shifting of the date plate 19 by rotating the screw shaft 12, to fill out properly the varying month-end dates. With this end in view the block 25a has one face provided with the row of numerals "29 30 31," which numerals are shown in Fig. 1 displayed both through the window 17 of the cover 9 and the sight opening 25 of the number plate 19, the geared relation of the two blocks to each other being such that when said numerals of the block 25a are brought into view the numerals "30 31" on one face of the block 26a will register with the opening 26 in the date plate 19, but the latter numerals will not be visible except when said date plate is shifted for columns leftward of the posi-

tion thereof shown in Fig. 1. Giving the shaft 13 a quarter turn in a direction moving upwardly the exposed face of the block 25a as viewed in Fig. 1 will bring into view the next row of numerals "29 30" (see Fig. 7) on said block, and at the same time will cause "30" on block 26a to register with the sight opening 26 of the date plate. Another quarter turn of shaft 13 in the same direction will bring "29" only into view through the sight opening 25 and will present to the front the first of the two blank faces of the block 26a. Still another like quarter turn of shaft 13 will present forwardly the single blank face of block 25a and the second of the blank faces of the block 26a.

What is claimed is:

1. In a calendar of the kind described, the combination, with a cover plate having through it a window to display a table of month dates, there being a row of week day indicators along an edge portion of said window; of a shiftable date plate having inscribed upon it vertical columns and horizontal rows of month day indicating numbers, the numbers of each column consecutively increased by seven when read downwardly and the numbers of each row being progressively one higher as read from left to right, said date plate having through it two sight openings positioned to have displayed through them month end dates in addition to those in the aforesaid table, said table ending with the number "28" located at approximately the midlength of said date plate and one of said sight openings being located immediately to the right thereof, the other of said sight openings being located immediately below the lower left hand position of said table, and a separate month-end number display means rotatably carried by said date plate behind each of said sight openings and collectively operable to display circumferentially arranged varying month-end date indicating numbers there-through.

2. In a calendar of the kind described, the combination, with a cover plate having through it a window to display a table of month dates, there being a row of week day indicators along an edge portion of said window; of a shiftable date plate having inscribed upon it vertical columns and horizontal rows of month day indicating numbers, the numbers of each column consecutively increased by seven when read downwardly and the numbers of each row being progressively one higher as read from left to right, said date plate having through it two sight openings positioned to have displayed through them month end dates in addition to those in the aforesaid table, said table ending with the number "28" located at approximately the midlength of said date plate and one of said sight openings being located immediately to the right thereof, the other of said sight openings being located immediately below the lower left hand portion of said table, a block rotatably mounted upon said shiftable plate behind each of said sight openings and inscribed with circumferentially arranged month-end day indicating numbers, and means to rotationally adjust said blocks so as to bring the proper month-end day indicating numbers into view through said sight openings.

3. The subject matter of claim 2, and said means for rotationally adjusting said blocks being connected with only one of them, and means whereby said one block is mechanically operatively connected to the other block so that the

latter block is properly adjusted when said one block is rotated to the desired position.

4. In a calendar of the kind described, the combination, with a cover plate having through it a window to display a table of month dates, there being a row of week day indicators along an edge portion of said window; of a shiftable date plate having inscribed upon it vertical columns and horizontal rows of month day indicating numbers, the numbers of each column consecutively increased by seven when read downwardly and the numbers of each row being progressively one higher as read from left to right, said date plate having through it two sight openings positioned to have displayed through them month end dates in addition to those in the aforesaid table, said table ending with the number "28" located at approximately the midlength of said date plate and one of said sight openings being located immediately to the right thereof, the other of said sight openings being located immediately below the lower left hand portion of said table, a screw rod rotatably mounted upon said cover plate in a supporting relation to said date plate for rotation to shift the latter plate to bring the number columns thereof into alignment with the proper week-day indications, a second rod rotatably carried by said cover plate in a subjacent parallel relation to said screw rod and extending through guide openings therefor in parts of said date plate, and turnable members carried by said date plate and positioned to display varying month-end date indicating numbers through said sight openings, said turnable members being operatively related to said second rod for being properly adjusted by the relation of the latter.

5. In a calendar of the kind described, the com-

bination, with a cover plate having through it a window to display a table of month dates, there being a row of week day indicators along an edge portion of said window; of a shiftable date plate having inscribed upon it vertical columns and horizontal rows of month day indicating numbers, the numbers of each column consecutively increased by seven when read downwardly and the numbers of each row being progressively one higher as read from left to right, said date plate having through it two sight openings positioned to have displayed through them month end dates in addition to those in the aforesaid table, said table ending with the number "28" located at approximately the midlength of said date plate and one of said sight openings being located immediately to the right thereof, the other of said sight openings being located immediately below the lower left hand portion of said table, a block 20 behind each of said sight openings and inscribed with circumferentially arranged month-end day indicating numbers, a rod whereon one of said blocks is mounted, a stub shaft whereon the other of said blocks is mounted, said rod and stub shaft being rotatably mounted upon said shiftable plate, and gearing whereby said rod-mounted block is mechanically operatively connected with the other block so that the latter is properly adjusted when said rod-mounted block is rotated to the desired position, said gearing including a gear 25 which is mounted upon said rod in a slidably, nonrotatable relation thereto.

6. The subject matter of claim 5, and a pair of flanges carried by said shiftable plate and positioned to maintain said rod-mounted block in registry with the sight opening with which it cooperates.

JONAS KAUFMAN.
